UNITED STATES PATENT OFFICE.

THOMAS F. MORRIN, OF JERSEY CITY, NEW JERSEY, ASSIGNOR TO
ELIZABETH T. MORRIN, OF JERSEY CITY, NEW JERSEY.

STEAM-BOILER.

SPECIFICATION forming part of Letters Patent No. 748,400, dated December 29, 1903.

Application filed April 14, 1902. Serial No. 102,825. (No model.)

To all whom it may concern:

Be it known that I, THOMAS F. MORRIN, a citizen of the United States, and a resident of Jersey City, Hudson county, New Jersey, 5 have invented certain new and useful Improvements in Steam-Boilers, of which the following is a specification.

My invention relates to steam-boilers of the inclined - water - tube type now commonly 10 known as the "Babcock & Wilcox" type, and has for its particular object to improve the construction of serpentine headers employed for the purpose of establishing and maintaining communication between the different sets 15 of water-tubes.

In the accompanying drawings I have shown a section of a serpentine header in which my invention is embodied.

In the drawings, Figure I is a face or front 20 view of a header embodying my invention. Fig. II is a transverse section thereof. Fig. III is a plan view, and Fig. IV is a side view, of the same.

In all of the figures mentioned I have shown 25 the interior construction by dotted lines, as is usual in such drawings.

In the drawings, *a* indicates the casing of the serpentine header, formed of two recessed 30 castings fitting together face to face. Number of columns of said serpentine headers fit together side by side.

b indicates tubes or thimbles which project 35 slightly inwardly and serve as expansion-faces, against which the ends of the general- 40 tor-tubes are expanded. These thimbles are arranged in pairs, and the pairs are staggered, so as to produce the serpentine form. The serpentine headers terminate in uptakes and 45 downtakes in the form of trunks *c* of a tubular form on the exterior, which for the purposes of strength are united by a web *d*. The inside diameter of the uptakes and 50 downtakes is greater than the inside diameter of the individual tubes fitting in the tubes *b* of

the headers. For this reason when the up- 45 take of one serpentine - header section is brought into communication with the down- take of another header-section a very effi- 50 cient circulation is provided for. Opposite each pair of tubes *b* is a hole *e*, closed by suit- 55 able hand-hole plate *f*, having a brace *g* and a bridge *h*, united by a suitable bolt *i* or other fastening means. The meeting faces of the plate and hole are preferably recessed, as shown, by a peripheral recess which receives 60 a strip *j*, of fusible packing, such as lead or other metal. The advantages of such construction are obvious. In the interior of the header I provide suitable ribs or baffle-strips *k*. These ribs or baffle-strips strengthen the 65 walls of the header and aid in maintaining the circulation.

Having described my invention, what I 70 claim, and desire to secure by Letters Patent, 75 is—

1. As a new and useful article of manufac- 70 ture, a serpentine-header section made in two sections and divided on a longitudinal plane and provided with superposed staggered pairs of tube-receiving apertures and terminating 75 at each end in a plurality of trunks of gen- 80 eral tubular form, united by the web *d*, and suitable ribs or strips *k* in the interior of the header.

2. As a new and useful article of manufac- 80 ture, a serpentine-header section made in two sections or parts divided on a longitudinal plane and comprising undulated side walls, superposed staggered pairs of tube-openings and terminating at each end with a pair of 85 trunks of general tubular form, united by the web *d*, a hand-hole opposite each pair or set of tubes and hand-hole plates *f* covering the hand-holes substantially as described.
